ELECTRIC RARE GAS FILLED LAMP

Anton Lederer, Vienna, Austria; Catherine Danzer and General Conrad Randa, executors of said Anton Lederer, deceased, assignors to Ernest Anton Lederer, Glen Ridge, N. J.

Application December 20, 1930, Serial No. 503,804
In Austria December 28, 1929

5 Claims. (Cl. 176—122)

This invention relates to electric rare gas filled lamps, and more especially to those of the class disclosed in my prior co-pending applications, Ser. No. 468,884 filed July 18, 1930, and Ser. No. 5 497,025 filed November 20, 1930, containing electrodes which are so spaced apart in relation to the rare gas pressure that the rare gas is excitable thereby to luminescence as an intense aureole.

In lamps of this kind which have hot electrodes or at least a hot cathode and wherein the rare gas filling sometimes with an admixture of other gases, has an addition of mercury, a rise in temperature in the interior of the lamp above that which is necessary for its proper operation is often disadvantageous owing to overheating or excessive evaporation of the mercury by which the lighting effect of the lamp is unfavourably influenced the lamp giving a bluish light. This phenomenon depends also on the position of the liquid mercury with respect to the gas filling of the discharge space. For instance, in the case of neon and other rare gas filled lamps containing an addition of mercury and oxide electrodes, hot electrodes heated by heating wires of a diameter of about 0.12 to 0.13 mm. for example, more or less evaporation of the mercury will take place, according to the position of the lighting portion of the lamp. This is because the part containing the liquid mercury may be more or less easily accessible to the heated neon gas; consequently the light which with proper evaporation of the mercury is white or nearly white is strengthened at the violet end of the spectrum by the formation of an excess of mercury vapour or by the overheating of the mercury so that the lamp 25 emits a bluish light.

According to the present invention this disadvantage is removed by locating the liquid mercury in the lamp in such a manner that it is not exposed directly or in its entirety to the heat 40 of the heated gas filling in the discharge space of the lamp. Excessive heating and evaporation of the mercury and consequently with some lamps a bluish light due to the mercury is thereby avoided.

45 One method of carrying out the invention is to locate the liquid mercury, and in some cases also the getter which is a material employed for the purpose of freeing the filling gas or gases from the last traces of impurities, in a part of the lamp beneath the discharge space. The liquid mercury is therefore not so directly, or at least not in its entirety, exposed to the action of the heated gases and excessive evaporation is 50 avoided. Also, the quantity of liquid mercury

to be introduced need not be measured exactly because the whole of the mercury will not evaporate. When however the liquid mercury is located above the discharge space, the exact and correct quantity of mercury is difficult to find, for instance, in the case of a lamp taking a current of from 0.4 to 0.5 ampere, because under the intense action of the circulating heated gases a very intense evaporation of the mercury takes place mostly extending to the whole amount of 10 mercury present.

15 It is advantageous to have the liquid mercury located beneath the discharge space in the neck of the lamp. This neck may be at any desired position in the lighting part of the lamp container, provided it is beneath the discharge space. In the case of an electric gas-filled lamp with a globe shaped glass bulb and a neck, the mercury, and in some cases the getter also, may be placed in the neck and the lamp is used in a 20 vertical or inclined position so that the neck extends downward perpendicularly or at an angle and consequently lies beneath the discharge space.

25 In another method of carrying out the invention the part of the lamp containing the liquid mercury, and in some cases the getter also, is separated from the discharge space of the lamp by a partition which does not prevent communication between these parts, that is to say the access of gas from one part to the other, but 30 renders it more difficult. The partition may be, for example, a plate leaving an annular passage free. By the partition an excessive evaporation of the mercury is prevented and the circulation 35 of the gas into the space which contains the liquid mercury is limited. The partition is preferably made of an insulating, heat insulating or electrically insulating material, such for instance as mica, glass, quartz or the like; it is further 40 advisable to use a transparent material for the partition.

Both the methods above described may be combined by locating the mercury and the getter in a neck lying beneath the discharge space, the interior of which neck is almost completely separated from the discharge space by means of a partition so arranged that between the interior of the neck and the discharge space the passage 45 of gas can still take place.

50 The accompanying drawing is a view, somewhat diagrammatic, illustrating by way of example only an electric lamp constructed in accordance with the invention.

55 Referring to the drawing, 1 is a globe or portion

of the lamp intended to emit light; 2 are the electrodes provided with leading in wires 3 and supported on supports 4 in an ordinary manner. The globe 1 has a downwardly extending neck 5 in which is located a ring 6 carried on a downwardly depending carrier 7 attached to one of the supports 4. 8 is the partition which is carried by the pinch or re-entrant part 9 of the container. The partition is of annular form with the re-entrant part 9 passing through the central orifice and is of such diameter that its edge is spaced apart from the neck as indicated at 10.

In the manufacture of the lamp the getter is located on the ring 6 and when vaporized deposits 15 on the neck portion 5 of the lamp bulb so that it does not interfere with the emission of light through the globe 1.

The liquid mercury is contained in the bottom 20 of the neck as shown at 11 and is screened from the direct heat of the discharge space in the globe 1 by the partition 8. Free communication between the space in the neck and the discharge space is allowed round the edge of the partition.

When a getter is used and vaporized from the 25 ring 6 it will deposit only on the neck portion.

No claim is made in this application for the construction of the light emitting portion of the lamp per se as shown in the upper part of the drawing, such being claimed in my co-pending 30 application hereinbefore referred to.

I claim:

1. An electric illuminating lamp comprising an envelope having a filling consisting of at least one rare gas, cooperating electrodes therein at least 35 one of which is of the indirectly-heated electron emissive type, means for applying a potential between said electrodes, said electrodes having such a spacing in relation to the rare gas pressure that the rare gas is excitable thereby to luminescence as an intense aureole, and a small quantity 40 of mercury located within said envelope in a position where it will be heated and vaporized by but only partly accessible to the circulating hot rare gas and so shielded from the heat thereof that the 45 mercury will be incompletely vaporized and thereby avoid predominance of mercury light.

2. An electric illuminating lamp comprising an envelope having a filling consisting of at least one rare gas, cooperating electrodes therein at least 50 one of which is of the indirectly-heated electron emissive type, means for applying a potential between said electrodes, said electrodes having such a spacing in relation to the rare gas pressure that the rare gas is excitable thereby to luminescence as an intense aureole, and a small quantity 55 of mercury located within a part of said envelope in a position where the mercury will be subject to the heat of the hot rare gas and be vaporized thereby, said mercury containing part of the envelope being removed from the gaseous discharge space and having such restricted com-

munication therewith in relation to the heating effect of the hot rare gas on the mercury in said position that the mercury will be vaporized incompletely and to an extent to produce a substantially white light.

3. An electric illuminating lamp comprising an envelope having a filling consisting of at least one rare gas, cooperating electrodes therein at least one of which is of the indirectly-heated electron emissive type, means for applying a potential between said electrodes, said electrodes having such a spacing in relation to the rare gas pressure that the rare gas is excitable thereby to luminescence as an intense aureole, a small quantity of mercury located in a part of said envelope which is out of 15 the gaseous discharge path, the mercury in said part of the envelope being in a position to be heated and thereby vaporized by the hot rare gas, and a partition largely but not completely screening said mercury from the gaseous discharge path 20 and shielding the mercury in said part of the envelope from the heat of the hot rare gas and thereby controlling the vaporization of the mercury so as to avoid predominance of mercury light.

4. An electric illuminating lamp comprising an envelope having a main portion and a neck portion through which electrical leads pass and having a filling consisting of at least one rare gas, 30 cooperating electrodes in the main portion of the envelope at least one of which is of the indirectly-heated electron emissive type, means for applying a potential between said electrodes, said electrodes having such a spacing in relation to the rare gas pressure that the rare gas is excitable thereby to luminescence as an intense aureole, a small quantity of mercury located in the neck portion of said envelope, and a partition providing a restricted communication passage between 35 said neck portion and the main portion of said envelope and shielding said neck portion from the heat of the gases in said main portion to such an extent in relation to said communication passage that the mercury will be vaporized to an extent which will avoid predominance of mercury light.

5. An electric illuminating lamp comprising an envelope having a main portion and a neck portion through which electrical leads enter, a filling of at least one rare gas and mercury vapor, 50 cooperating electrodes in the main portion of the envelope at least one of which is of the indirectly-heated electron emissive type, said cooperating electrodes being capable of exciting both the rare gas and the mercury vapor to luminescence simultaneously, a getter substance deposited on said neck portion of the envelope, and a partition mainly but incompletely separating said neck portion from the main portion of the envelope.

ANTON LEDERER.
